(57) **CLAIM**

The ornamental design for a nasal mask, as shown and described.

DESCRIPTION

FIG. 1 is a front perspective view of a nasal mask showing our new design;

FIG. 2 is a rear perspective view thereof;

FIG. 3 is a front elevational view thereof;

FIG. 4 is a rear elevational view thereof;

FIG. 5 is a side elevational view thereof, the opposite side being a mirror image thereto;

FIG. 6 is a top plan view thereof; and,

FIG. 7 is a bottom plan view thereof.

The portions drawn in broken lines are shown for illustrative purposes only and do not form part of the claimed design.
